CLAIM

The ornamental design for a microwave cooking device, as shown and described.

DESCRIPTION

FIG. 1 is a front top perspective view showing my new design;

FIG. 2 is a front view thereof;

FIG. 3 is a rear view thereof;

FIG. 4 is a top view thereof, showing the center features in a first position of use;

FIG. 5 is a top view thereof, showing the center features in a second position of use.

FIG. 6 is a bottom inner view thereof; and

FIG. 7 is a left side view thereof

FIG. 8 is right side view thereof; and,

FIG. 9 is a perspective view thereof.

The broken lines in FIG. 6 show portions of the microwave cooking device that form no part of the claimed design.

The broken lines in FIG. 9 show environment structure and form no part of the claimed design.

1 Claim, 9 Drawing Sheets
